WASHING MACHINE

John T. Hume, Chicago, Ill., assignor to Electric Household Utilities Corporation, Cicero, Ill., a corporation of Illinois

Application February 8, 1929, Serial No. 338,456

11 Claims. (Cl. 74—79)

This invention relates to improvements in washing machines and its purpose is to provide a simplified and improved form of washing machine adapted primarily for household use. The principal object of the invention is to provide an improved washing machine of the tub type embodying improved power driven clothes agitating means. A further object of the invention is to provide a washing machine embodying improved driving mechanism for the clothes agitating device. Still another object of the invention is to provide a washing machine and a clothes wringer in combination with improved driving mechanism by which either the clothes wringer or the clothes agitating device of the washing machine may be driven. Another object is to provide an improved form of clothes agitating device. Other objects relate to various features of construction and arrangement which will appear more fully hereinafter.

The nature of the invention will be understood from the following specification taken in connection with the accompanying drawings, in which one embodiment is illustrated.

In the drawings, Figure 1 shows a vertical axial section through a washing machine embodying the features of the present invention, illustrating the associated clothes wringer in elevation;

Fig. 2 shows a horizontal section taken on the line 2—2 of Fig. 1;

Fig. 3 shows a detail vertical section taken on the line 3—3 of Fig. 2, illustrating the mounting of the driving motor;

Fig. 4 is a detail sectional view taken on the line 4—4 of Fig. 2, illustrating the construction of the drain outlet;

Fig. 5 shows an enlarged vertical section, like that of Fig. 1, illustrating the construction of the driving mechanism;

Fig. 6 shows a top plan view of the driving mechanism illustrated in Fig. 5;

Fig. 7 is a detail plan view, similar to that of Fig. 6, illustrating the relation of the parts when the driving mechanism of the clothes agitator is disengaged;

Fig. 8 is an enlarged vertical section taken on the line 8—8 of Fig. 1, illustrating the construction of the driving mechanism of the clothes wringer;

Fig. 9 is an enlarged vertical section taken on the line 9—9 of Fig. 8;

Fig. 10 shows a detail vertical section taken on the line 10—10 of Fig. 8;

Fig. 11 shows a horizontal section taken on the line 11—11 of Fig. 9; and

Fig. 12 shows a horizontal section taken on the line 12—12 of Fig. 8.

As illustrated in the accompanying drawings, the improved washing machine of the present invention comprises a sheet metal clothes containing vessel 15 of the tub type which is provided with an outer cylindrical wall 15a open at its upper end and provided around its upper edge with an inwardly extending bead 15b. A circular sheet metal cover 16 is adapted to close the upper open end of the tub 15 and this cover is provided with an annular downwardly extending flange 16a which is adapted to fit over the upper end of the tub 15 and to engage an outwardly directed bead 15b which is formed on the tub. The cover 16 inclines downwardly and inwardly from its outer edge and terminates in an annular downwardly turned bead 16b which bounds a circular opening 17. This opening 17 is normally closed by a removable lid 18 having an outwardly directed annular shoulder 18a which overlies the upper edge of the cover above the bead 16b. The lid 18 is also provided with a downwardly extending annular flange 18b arranged to fit within the annular bead 16b, as shown in Fig. 1. The central portion of the lid 18 is depressed as shown at 18c and is provided with a handle 19 adapted to be engaged by the fingers of the operator. The vessel 15 is mounted on and secured to a circular sheet metal frame 20 having a downwardly extending annular flange 20a which is secured to a plurality of supporting legs 21 provided at their lower ends with casters 22 adapted to rotate about vertical axes and to rest upon the floor or other support 23.

Within the clothes receiving vessel 15, there is located a clothes agitating device 25 comprising an upwardly extending hollow stem 25a having the lower portion thereof formed integrally with an outwardly directed base plate or skirt 25b. Three equally spaced vertically extending ribs or vanes 25c unite the skirt 25b with the stem 25a and also serve as clothes agitating members 45 when the device 25 is oscillated about a vertical axis. The lower portion of the stem 25a of the clothes agitating device is journaled on a bushing 26 which is mounted on the lower portion of a hollow sleeve 27 provided at its lower end 50 with an outwardly flared portion 27a which is attached to the lower wall of the vessel and to the circular frame member 20 by means of bolts 28 which serve also to secure in place a housing 29 adapted to serve as a packing chamber around 55

the lower portion of a vertical driving shaft 30. This shaft extends upwardly through the hollow sleeve 27 and has a bushing 31 keyed on the upper end thereof. This bushing is journaled in the upper end of the sleeve 27 and is also keyed to the hub 25^d of the clothes agitating device so that when the shaft 30 is oscillated, a corresponding oscillatory motion is imparted to the clothes agitating device. Suitable precautions are taken for preventing leakage from the vessel 15 at the points where the outwardly flared portions 27^a of the supporting sleeve 27 are attached to the bottom of the vessel and to the supporting frame 20. Adjacent the outer edge of the vessel 15, at a suitable point, there is located an outlet valve casing 33 having the construction illustrated particularly in Fig. 4. This valve casing is secured beneath the frame member 20 by a hollow threaded plug 34 engaging an aperture in the bottom wall of the vessel 15 and a corresponding aperture in the frame 20. The casing 33 is provided with a valve seat 33^a and the valve member 33^b is adapted to engage this seat to control the flow of washing fluid outwardly to the mouth 33^c of the valve casing. The valve member 33^b is mounted on a stem 33^d which threadedly engages the valve casing and which projects through the depending flange 20^a of the frame, terminating in a pair of ears 33^e.

30 The driving shaft 30 of the clothes agitating device 25 is driven through suitable driving mechanism operated by an electric motor 35, the casing of which is secured by studs 36 on a sheet metal bracket 37 secured to the under side of the frame 20 by bolts 38, as shown in Fig. 3. The conductors for the electric circuit lead to this motor through a flexible conduit 39 which enters a connecting block 40 mounted on the motor casing. The switch for controlling this circuit may be located conveniently to permit the ready starting and stopping of the driving mechanism. The shaft 41 of the motor 35 extends into a gear housing 42 secured to the under side of the frame 20 by means of bolts 45 engaging the holes 43 formed in the housing around its outer edge, as shown in Fig. 6. This gear housing is closed on its upper side by a sheet metal plate 44 secured in place by the bolts which secure the housing in position and this gear casing is adapted to contain oil or grease for the driving mechanism, which lubricant may be withdrawn through an opening normally closed by the plug 45. The motor shaft 41 is journaled in bearings 46 and it has secured thereon a spiral gear 47 adapted to mesh with the large gear 48. The gear 48 has its hub journaled on the stationary vertical shaft or axle 49 which is secured in a housing 50 carried by the lower part of the gear casing 42, as shown in Fig. 5. The upper portion of the hub of the gear 48 carries an integrally formed eccentric 51 which is adapted to revolve in a circular aperture 52^a formed in the eccentric block 52. This block is adapted to slide in guides 53 which are formed on the sides of an oscillatory arm or frame 54. This frame is provided at one end with a segmental gear 55 arranged to mesh with a pinion 56 secured on the lower end of the shaft 30 of the clothes agitating device so that when the frame 54 is oscillated by the rotation of the eccentric 51, an oscillatory motion is imparted to the clothes agitating device. The lower end of the shaft 30 is journaled in the bearing 57 formed in the gear casing 42, as shown in Fig. 5, and the pinion 56 rests on the

upper end of this bearing and is secured against vertical displacement by a transverse pin 58, thus forming a thrust bearing for the vertical driving shaft 30. The oscillatory frame 54 is provided at the end thereof opposite the segmental gear 55 with a bearing hub 59 adapted to rock about a cylindrical bearing member 60 which is carried by a plate 61. Both the hub 59 and the cylindrical bearing member 60 rest on the upper surface of a gear 62 which is splined on the lower end of a vertical operating shaft 63 and this gear 60 is arranged to be driven through an intermediate pinion 64 from the large driving gear 48 previously described. The pinion 64 meshes directly with both the gear 48 and the gear 60 and is journaled on a sub-shaft 65 extending upwardly from the lower wall of the casing 42. The gear 62 has a hub 62^a extending downwardly therefrom and journaled in a bearing 66 carried by the lower part of the gear casing and the downward thrust of this gear and of the shaft 63 are supported by a roller thrust bearing 67. The shaft 66 is adapted to drive the clothes wringer through the mechanism hereinafter described. For the purpose of permitting the driving mechanism of the clothes agitating device 25 to be connected and disconnected as desired, arrangements are made for disengaging the segmental gear 55 from the driving pinion 56 by shifting the oscillatory frame 54. This operation is effected by moving the cylindrical bearing 60 carried by the plate 61 which is pivoted to swing about a stationary pin 68 which extends downwardly from the vertically extending housing 70 in which the vertical operating shaft 63 is mounted. The plate 61 is provided with an elongated slot 61^a in which is mounted a block 71 provided with a circular aperture which is engaged by a pin 72 centrally located on a cylindrical block 73 which is journaled in a recess 74 formed in the lower part of the housing 70. The cylindrical member 73 carrying the eccentric pin 72 is secured to the lower end of a rod 75 which is journaled in the bearing 76 carried by the housing 70 and provided at its upper end with a crank handle 77 which may be manipulated to throw the segmental gear 55 into or out of mesh with the pinion 56. The block 71 is mounted to slide in the guide 69 which is directed radially outward from the axis of the pin 68 and the block 71 is normally forced in an outward direction by means of a coil spring 78 which is located in the slot 69. The axis of the rod or shaft 75 is so located with respect to the pin 72 and the block 71 that the spring 78 tends to hold the plate 61 in either extreme position to which it may be moved by the movement of the crank handle 77 at the upper end of the rod 75. When the rod 75 is rotated to turn the plate 61 to a position wherein the segmental gear 55 and the pinions 56 are disengaged, the oscillatory frame 54 is permitted to rock about the bearing member 60 without effecting movement of the clothes agitating device 25 while at the same time permitting the upwardly extending operating shaft 63. It will be noted that the shaft 63 extends through the apertures 79 formed in the guide member 69 and the plate 61, this aperture being large enough to permit the necessary shifting of the bearing member 60 without the walls of the aperture 79 contacting with the shaft 63.

As shown in Fig. 1, the housing 70 extends upwardly at the side of the clothes receiving ves-

sel 15 and, adjacent the upper edge of the vessel, it is outwardly flared as shown at 70^a. This tapered portion 70^a of the housing is adapted to be rotatably engaged by a similarly tapered sleeve 80 extending downwardly from and formed integrally with the housing 81 of the clothes wringer 82. An outwardly and downwardly extending flange 83 is formed on the housing 81 around the upper end of the sleeve 80 and this flange is adapted to rest on and extend downwardly around the outwardly extending flange 70^b which is formed on the casing 70. As shown particularly in Fig. 12, this flange 70^b is provided with a plurality of notches 84 any one of which may be engaged by a locking pin 85 mounted to slide vertically in suitable guides carried by the housing 81 and the housing cover 86. The housing is secured in place by cap screws 87. A sleeve 88 is secured on the pin 85 above the trough 89 in which the pins slide and a coil spring 92 is mounted on this sleeve between the lower annular shoulder 88^a thereof and the plate 90 which is secured to the under side of the cover 86 by means of screws 91. The sleeve 88 is adapted to engage an aperture 90^a formed in the plate 90 so that the pin 85 may be pulled upwardly by means of the handle 85^a mounted on the upper end thereof to cause the sleeve 88 to be raised against the compression of the spring 92, thus permitting the housing 81 and the wringer 82 to be rotated to any desired angular position with respect to the washing machine casing 15 after which the wringer may be locked in that position by causing the pins 85 to engage the desired one of the notches 84 in the flange 70^b.

The upper end of the vertical operating shaft 63 has a driving engagement with the hub 93^a of a bevel gear 93 which is mounted in the housing 81, the hub 93^a being journaled in a bearing 94 formed in the lower part of this housing, as illustrated in Figs. 8 and 9. The bevel gear 93 meshes continuously with two other bevel gears 95 and 96 which have their hubs journaled in bearings 97 and also rotatably mounted on a horizontal shaft 98. A clutch member 99 is mounted on the shaft 98 between the bevel gears 95 and 96 and is provided with clutch teeth 100 adapted to engage the clutch teeth 101 on the inner faces of the bevel gears 95 and 96 so that a driving connection may be established between the bevel gear 93 and the shaft 98 to cause this shaft to rotate in either direction depending upon the position of the clutch member 99 which is splined thereon.

The clothes wringer 82 is provided with a pair of oppositely rotating rolls 103 each of which is provided with shafts 104 engaging bearing members 105 which are mounted in the wringer frame 106. The shaft 104 of the lower roll is connected at one end through a coupling 106 with the shaft 98 upon which the clutch member 99 and the bevel gears 95 and 96 are mounted. By shifting the clutch member 99, the direction of rotation of the rolls 103 of the wringer may be reversed and this reversal is effected by shifting the clutch member on the central enlarged portion of the shaft 98 on which it is splined. The clutch member has two annular flanges 99^a, forming a central annular groove 108. This annular groove is engaged by a block 109 having an aperture therein which is rotatably engaged by a stud 110 located in an eccentric position on the lower end of a rotatable shaft 111. This shaft is journaled in a bearing 112 carried by the housing cover

86 and it has an operating handle 113 secured on the upper end thereof for manipulation by the operator in effecting the shifting of the clutch member 99. It will be apparent that when the crank handle 113 is rotated about its vertical axis, the corresponding rotation of the shaft 111 will shift the clutch member 99 in one direction or the other to effect a driving engagement between the shaft 98 and one of the bevel gears 95 or 96. In order that the clutch member 99 may be held in neutral position shown in Fig. 9 or in either of its engaging positions, the cover 86 of the wringer housing is provided with a recess 114 in which is located a ball 115 pressed downwardly by a coil spring 116. This ball is adapted to engage any one of the depressions 117 which are formed in the spring plate 118 shown particularly in Figs. 8 and 11. This spring plate 118 serves as a locking plate and it is mounted to rotate with the shaft 111 by being seated on the lower enlarged portion thereof and by having a tongue 118^a pressed downwardly therefrom to engage a key-way formed in the side of the lower end of the shaft. The locking plate 118 therefore rotates with the shaft 111 and the holes 117 are so located that one of them will be engaged by the spring pressed ball 115 when the clutch member 99 is in either a neutral position or in either of its engaging positions wherein the teeth 100 interlock with one of the sets of teeth 101. By this arrangement, the shaft 63, which rotates continuously when the driving motor 35 is in operation, may be employed when desired to operate the clothes wringer and may be allowed to rotate during the intervening intervals without effecting any operation of the wringer. The wringer 82 may therefore be operated simultaneously with the operation of the clothes agitating device or either the clothes wringer or the clothes agitating device may be separately operated. The spring plate 118 has a notch 118^a in the edge thereof which is adapted to register with the sleeve 88 when the clutch member 108 is in its neutral position, thus preventing the upward movement of the pin 85 and the connected sleeve 88 when the clutch member is in engagement with either of the clutch teeth 101. By this means, the operator is prevented from releasing the pin 85 from engagement with any one of the notches 84 to permit the rotation of the wringer on the supporting casing 70 when a driving connection is established through the rolls 103 of the wringer.

Although one form of the invention has been shown and described by way of illustration, it will be understood that it may be constructed in various other embodiments within the scope of the appended claims.

I claim:

1. The combination in driving mechanism for a clothes washing machine, of an operating shaft, a pinion fixed on said shaft, a frame having teeth adapted to mesh with the teeth of said pinion, a bearing member on which said frame is journaled, means for imparting an oscillatory motion to said frame, a block carrying said bearing member, and means for shifting said block and said bearing member bodily for causing said teeth of said frame to engage and disengage said pinion.

2. The combination in driving mechanism for a clothes washing machine, of an operating shaft, a pinion fixed on said shaft, a frame having teeth adapted to mesh with said pinion, means for imparting an oscillatory motion to said frame,

- a bearing member on which said frame is pivotally mounted, a pivoted plate carrying said bearing member, and manually operated means for turning said plate around its pivot for shifting the position of said bearing member and said frame.
3. The combination in driving mechanism for a clothes washing machine, of an operating shaft connected to said device, a pinion fixed on said shaft, a frame having teeth adapted to mesh with said pinion, means for imparting an oscillatory motion to said frame, a bearing member on which said frame is pivotally mounted, a pivoted plate carrying said bearing member, manually operated means for turning said plate around its pivot for shifting the position of said bearing member and said frame, and means associated with said plate for holding said bearing member in either of two extreme positions.
4. The combination in driving mechanism for a washing machine, of an operating shaft, a pinion fixed on said shaft, a pivotally mounted frame having teeth adapted to mesh with said pinion, a block slidably mounted in said frame, a rotatable member having an eccentrically located part rotatably engaging said block, means for rotating said member to effect the reciprocation of said block and the oscillation of said frame, and means for shifting said frame longitudinally to effect the disengagement of its teeth with those of said pinion.
5. The combination in driving mechanism for a clothes washing machine, of an operating shaft, a pinion fixed on said shaft, a frame having teeth adapted to mesh with said pinion, a bearing member on which said frame is pivotally mounted, means for imparting an oscillatory motion to said frame, a pivoted plate carrying said bearing member, said plate having a groove therein, a block slidably mounted in said groove, and means comprising an eccentric pin for moving said block in said groove to move said plate about its pivotal connection and thereby shift the position of said bearing member and said frame.
6. The combination in driving mechanism for a washing machine, of an operating shaft, a pinion fixed on said shaft, a frame having teeth adapted to mesh with said pinion, a wringer shaft, a second pinion fixed on said wringer shaft, means including a common driving gear for actuating said frame and said second-named pinion, a bearing member loosely surrounding said wringer shaft and having said frame pivotally mounted thereon, and means for shifting the position of said bearing member with respect to said wringer shaft for controlling the engagement of the teeth of said frame with said first named pinion.

7. The combination in driving mechanism for a washing machine, of an operating shaft, a pinion fixed on said shaft, a pivotally mounted frame having teeth adapted to mesh with said pinion, a rotatable driving member, a member eccentrically located on said driving member and having a sliding engagement with said frame, means for rotating said driving member to effect the oscillation of said frame, and means for shifting said frame longitudinally to effect the disengagement of its teeth with those of said pinion. 5

8. The combination in driving mechanism for a washing machine, of an operating shaft, a pinion fixed on said shaft, a pivotally mounted frame having teeth adapted to mesh with said pinion, a driving gear mounted adjacent said frame, an eccentric operated by said driving gear, a block slidably mounted in said frame and rotatably engaged by said eccentric, and means for rotating said driving gear. 15

9. The combination in driving mechanism for a washing machine, of an operating shaft, a pinion fixed on said shaft, a frame having teeth adapted to mesh with said pinion, a wringer shaft, a second pinion fixed on said wringer shaft, an intermediate gear meshing with said last named pinion, a common driving gear meshing with said intermediate gear, and means including an oscillatory rack pivoted about said wringer shaft and actuated by said driving gear for operating said first 30 named pinion. 25

10. The combination in driving mechanism for a washing machine, of an operating shaft, a pinion fixed on said shaft, a frame having teeth adapted to mesh with said pinion, a wringer shaft, a second pinion fixed on said wringer shaft, an intermediate gear meshing with said last named pinion, a common driving gear meshing with said intermediate gear, means including a pivotally mounted oscillatory rack bar pivoted about said 40 wringer shaft and actuated by said driving gear for actuating said first named pinion, and means for shifting the pivotal mounting of said rack bar to disengage said rack bar from said first named pinion. 45

11. The combination in driving mechanism for a washing machine, of an operating shaft, a pinion fixed on said shaft, a frame having teeth adapted to mesh with said pinion, a wringer shaft, said frame being pivoted to swing about the axis of said wringer shaft, a second pinion fixed on said wringer shaft, and means including a common driving gear for actuating said frame and said second named pinion. 50

JOHN T. HUME. 55
